CLAIM

The ornamental design for a woodworking clamp, as shown.

DESCRIPTION

FIG. 1 is a front elevational view of a woodworking clamp showing my new design;

FIG. 2 is an enlarged top plan view thereof;

FIG. 3 is an enlarged side elevational view thereof with the guide partly broken away for convenience of illustration;

FIG. 4 is an enlarged side elevational view of the side opposite that shown in FIG. 3 with the guide partly broken away for convenience of illustration;

FIG. 5 is an enlarged bottom plan view thereof;
 FIG. 6 is a front elevational view thereof showing the upper jaw raised and the cam lever in engaging position; and

FIG. 7 is a reduced perspective view thereof showing the upper jaw raised and the cam lever in non-engaging position.

FIG. 2
